UNITED STATES PATENT OFFICE

GERHARD RADKE, OF BERLIN, GERMANY, ASSIGNOR TO SIEMENS & HALSKE AKTIEN-
GESELLSCHAFT, OF WERNERWERK, SIEMENSSTADT, NEAR BERLIN, GERMANY

AUTOMATIC TELEPHONE SYSTEM

Application filed May 13, 1929, Serial No. 362,500, and in Germany July 5, 1928.

In telephone systems with several exchanges and automatic working it is known that after a calling line has been connected to a junction line outgoing in a particular traffic direction it can be switched over to a junction line outgoing in another traffic direction when the numerical selection has indicated that a connecting route is to be set up in the latter traffic direction. Now, the object of the invention is to get the utmost use out of the switching devices that initiate the switching-over of the calling line and to reduce as far as possible the number of these devices, in some cases even altogether avoiding the use of special switching devices.

According to the invention, this is achieved in that a connecting device, which is located in the calling subscriber's exchange and in accordance with the number impulses transmitted connects a calling subscriber's line with junction lines going in different traffic directions, is controlled by switching devices which are located in different exchanges (for example, in the calling sub-exchange UVSt 1 and in the main exchange HVSt 1) and are under the influence of the calling party.

The circuits 1—7 show methods of carrying out the invention. Thus, Fig. 1 shows diagrammatically the arrangement of several exchanges.

In Fig. 2 is shown the call seeker AS, which can be reached by the subscriber Tn 1 in the sub-exchange UVSt 1 shown in Fig. 1, and the preselector VW, which serves to switch over in the different traffic directions.

Fig. 3 shows a further portion of the connecting devices located in the sub-exchange UVSt 1.

Fig. 4 represents a further portion of the connecting device located in the sub-exchange UVSt 1 and, in addition, it shows the main exchange HVSt 1, which can be reached over a two-wire junction line VL.

Fig. 5 shows a part of the connecting devices located in the sub-exchange UVSt 3 (see Fig. 1).

Figs. 6 and 7 show other forms of construction for the junction lines going to the main exchange HVSt 1 (three-wire junction lines).

The rectangles enclosing the windings of certain of the relays, such as T, R, V, and S of Fig. 1 indicate that these relays are made slow-acting by the addition of a copper slug on the core of the relay or in any other manner well known in the art.

By means of Fig. 1, a synopsis will first be given of the traffic-carrying devices accessible to the subscriber Tn 1.

On taking down his receiver, the subscriber Tn 1 over a call seeker AS and over a preselector VW in position 1 of the latter reaches a group selector GW 1 of the sub-exchange UVSt 1. If he wishes to reach a local subscriber (for example, Tn 2) of the same sub-exchange UVSt 1, he will reach him over the group selector GW 1 and the final selector LW 1 of the sub-exchange UVSt 1.

But, if he wishes to reach a subscriber of another exchange, he will, by dialling a certain number for effecting a switching-over at the group selector GW 1, first move on the preselector VW to the contact 2 and so release the group selector GW 1 in the sub-exchange UVSt 1. This moving-on causes the subscriber Tn 1 to seize a junction line of the main exchange HVSt 1 over an intermediate switch ZW and a repeater Ue; and over that junction line he reaches a group selector GW 4 in the main exchange HVSt 1.

The insertion of an intermediate switch functioning as a non-numerical switch renders this junction line also available to incoming trunks from other sub-exchanges. In accordance with the impulse train transmitted, the subscriber Tn 1 will now reach either a main exchange subscriber (for example, Tn 3) over a group selector GW 4 and a final selector LW 4 in the main exchange HVSt 1,

or a junction line going to another main exchange over a group selector GW 4 of the main exchange HVSt 1 standing on a certain level. Furthermore, by suitably operating a device (in Fig. 1 an auxiliary switch MW) located in the main exchange HVSt 1, the subscriber Tn 1 can also make use of other connecting routes.

Thus, if the transmitted impulse train be such that by means of the auxiliary switch MW the preselector VW in the sub-exchange UVSt 1 be moved onto the

55

100

contact 3, the subscriber T_n 1 can release the connecting devices which have been positioned in the main exchange $HVSt$ 1, and can reach a subscriber (for example, T_n 4) of the sub-exchange $UVSt$ 3 over a group selector GW 3 and a final selector LW 3 at that sub-exchange $UVSt$ 3.

If, however, the transmitted impulse train be such that the preselector VW in the sub-exchange $UVSt$ 1 be moved back to the contact 1, the subscriber can reach, for example, the subscriber T_n 5 over a group selector GW 1 in the sub-exchange $UVSt$ 1, which in some cases may be the same as the group selector to be positioned when setting up a connection to a local subscriber of the sub-exchange, and over a group selector GW 2 and a final selector LW 2 in the sub-exchange $UVSt$ 2 of the same main exchange.

20 The above-mentioned possible connections will now be further explained with reference to the other figures.

When the subscriber T_n 1 (Fig. 2) takes down his receiver, the two-step relay T is energized over: earth, battery, resistance Wi , contact 1 t , subscriber T_n 1, contact 2 t , winding I of relay T , earth. The relay at first only closes its contacts 3 t and 5 t . The closing of the contact 5 t energizes the relay R over: earth, battery, relay R, contacts 4 p , 5 t , earth. The closing of the contact 13 r energizes the rotary magnet D 1 of the call seeker AS over: earth, relay interrupter RU 1, contacts 11 h , 12 t 1, 13 r , 14 p , rotary magnet D 1, battery, earth. When the call seeker AS has found the calling subscriber, the following circuit is established: earth, contacts 26 v , 24 r , windings I and II of relay P, wiper c 1 of call seeker AS, lead c, contact 3 t , winding II of relay T, battery, earth. Relay P is operated in this circuit and short circuits its high resistance winding II at contact 25 p ; by opening the contact 14 p it arrests the call seeker AS; at contacts 19 p and 20 p it switches through the leads a and b to the preselector VW and at contact 4 p it opens the energizing circuit of relay R. In the circuit of relay P the winding II of relay T is also traversed by current; hence, this relay now operates in its second step, so that the circuit for energizing the winding I of relay T is opened at the contacts 1 t and 2 t .

The leads a and b having been switched through, the relay A is energized over: earth, battery, winding I of relay A, contacts 22 t 1, 19 p , wiper a 1 of the call seeker AS, lead a, subscriber T_n 1, lead b, wiper b 1 of the call seeker AS, contacts 20 p , 28 t 1, winding II of relay A, contact 31 s , earth. Thereby relay V is energized over: earth, contact 7 a , relay V, battery, earth. Furthermore, the preselector VW is started up to hunt owing to the rotary magnet D 2 being energized over: earth, battery, rotary magnet D 2, con-

tacts 60 s , 59 a , 58 t 1, 57 h , relay interrupter RU 2, earth.

The circuit of the thermic relay TH is also closed at contacts 15 v and 18 a but this relay does not operate immediately. If no free junction line is available the circuit of the thermic relay TH remains closed and after an interval this relay operates, and at its contact 56 th closes an energizing circuit for winding I of relay S. Relay S operates and at its contact 30 s completes a locking circuit for itself over winding II and transmits the busy tone to the calling subscriber over: earth, bes., contact 30 s , winding II of relay A, contacts 28 t 1, 20 p , wiper b 1 of the call seeker AS, lead b of the subscriber's line, subscriber's station T_n 1, lead a of the subscriber's line, wiper a 1 of the call seeker AS, contacts 19 p , 22 t 1, winding I of relay A, battery, earth. Relay S also opens the circuit of the rotary magnet D 2 at contact 60 s thereby stopping the preselector VW in its hunting operation.

When the preselector VW finds a free junction line, for example the one having the leads a 3, b 3, c 3, d 3, e 3 going to the connecting device shown in Fig. 3, a circuit is closed over: earth, battery, windings I and II of relay T 1, contacts 41 a , 39 s , 37 q , 35 u , wiper c 2 of the preselector VW , lead c 3, thermic relay TH 1, winding I of relay C, vertical off-normal contact 64 k , rotary off-normal contact 65 w , earth. The relays T 1 and C are operated in this circuit. The opening of contact 58 t 1 arrests the preselector VW . A locking circuit for relay A and an energizing circuit for the relays H and Y are closed at contact 21 t 1 over: earth, contact 21 t 1, relay Y, relay H, winding I of relay A, battery, earth. At contacts 23 t 1 and 29 t 1 the junction line is switched through to the leads a 3 and b 3; hence the relay A 1 (Fig. 3) is now energized over the subscriber's loop. Relay C having been energized, the contact 67 c closes a locking circuit for relay C and an energizing circuit for the relay V 1 over: earth, contact 67 c, winding II of relay C, contact 69 a 1, relay V 1, battery, earth. The closing of contact 66 v 1 connects the resistance Wi in parallel with relay C to the lead c 3.

If the subscriber T_n 1 does not transmit any impulses within a given time, the thermic relay TH 1 is operated over the above-described circuit for energizing the relays T 1 and C; hence the contact 62 th 1 is closed and thereby the relay S is energized over: earth, contact 62 th 1, lead d 3, wiper d 2 of the preselector VW , contacts 51 x , 54 y , 55 a , winding I of relay S, battery, earth. At contact 39 s is opened the circuit for energizing the relays C and T 1; hence the connecting device (Fig. 3) seized in the sub-exchange $UVSt$ 1 is released and the subscriber T_n 1 receives the busy signal over: earth, bes., contact 30 s , winding II of relay A, contacts 28 t 1, 120

20 p , wiper b 1 of the call seeker AS, lead b , subscriber Tn 1, lead a , wiper a 1 of the call seeker AS, contacts 19 p , 22 t 1, winding I of relay A, battery, earth. During this time 5 the relay S locks itself over: earth, battery, winding II of relay S, contacts 32 a , 30 s , bes , earth.

But, if the subscriber transmits number impulses within the given time, the relay A1 10 is released at each impulse and over a contact of this relay are operated the driving magnets of a connecting device, such as GW1, which is partly shown in Fig. 3 and is located in the sub-exchange UVSt1 and selects a desired route. If the group selector GW1 is 15 operated to the first level or any other level assigned to local subscribers, an idle final connector, such as LW1, is seized and the dialling of two additional digits connects the calling subscriber to a subscriber in the same 20 sub-exchange UVSt1. In the example shown, the tenth level is used to designate an outgoing call while the second level is used for trunks to the sub-exchange UVSt2. The remaining 25 levels may be used for local traffic. Thus if the digits 1, 2 and 3 were dialled the calling subscriber would be connected to subscriber Tn 2 of the same sub-exchange UVSt1.

But, if the subscriber Tn 1 wants a subscriber of some other exchange, he must first 30 dial a designating digit. In our example it is assumed that this is the digit 0. Therefore, if the subscriber transmits 10 impulses, the switch GW1 which is located in the sub-exchange UVSt1, is raised to the tenth level. When this has been reached, the level contact 35 ko is mechanically operated so that the following circuit is established: earth, contacts 63 ko , lead e 3, wiper e 2 of the preselector 40 VW, contacts 49 x , 48 h , 43 x , 42 q , winding II of relay U, battery, earth. Relay V2 was energized at the first interruption at the beginning of the impulse train over: earth, contacts 67 c , 68 a 1, relay V2, relay V1, battery, 45 earth; but restored to normal a short time after the cessation of the impulse train. Relay U locks itself over: earth, battery, winding II of relay U, contacts 42 q , 43 x , 46 u , 52 s , 53 v , earth. The contacts 35 u and 36 u open 50 the circuit for energizing the relay T1 and prepare the test circuit over the wiper d 2 of the preselector VW. After the release of relay T1, the relays H and Y also fall back; hence the rotary magnet D2 of the preselector 55 VW is energized over: earth, battery, rotary magnet D2, contacts 60 s , 59 a , 58 t 1, 57 h , relay interrupter RU2, earth; and the preselector VW is moved on the hunt for a junction going to the main exchange HVSt1 over a repeater 60 Ue. Furthermore, after the preselector VW has moved on, the relay A1 (Fig. 3) falls back; hence the short circuiting of winding II of relay C at contact 68 a 1 causes this relay to fall back also, and at contact 67 c it 65 opens the circuit for energizing the relay V1.

Contacts of this relay can then in some manner bring about the release of the positioned switch (not shown). After the release of relay Y (Fig. 2) the relay X is energized over: earth, battery, relay X, contacts 45 y , 46 u , 52 s , 53 v , earth, and it later on locks itself over its contact 44 x .

When the preselector VW has found an idle junction line (a 4, b 4, c 4, d 4) over which can be reached the main exchange HVSt1, the following circuit is established: earth, contacts 86 a 3, 88 v 5, 84 h 1, 85 h 2, lead d 4, wiper d 2 of the preselector VW, winding I of relay U, contacts 36 u , 37 q , 39 s , 41 a , windings I and II of relay T 1, battery, earth. In this circuit is operated the relay T 1, and after relay A 3 has been energized over the speaking loop by the switching through at the contacts 23 t 1 and 29 t 1, the relay C 2 is also operated, which till now has been short circuited over contact 86 a 3. Therefore, after relay T 1 has been energized, the preselector is arrested and the relays H and Y are energized in the manner already described. The before-mentioned energizing of the relay A 3 takes place over: earth, battery, relay A 3, lead a 4, wiper a 2 of preselector VW, contacts 23 t 1, 19 p , wiper a 1 of the call seeker AS, lead a , subscriber Tn 1, lead b , wiper b 1 of the call seeker AS, contacts 20 p , 29 t 1, wiper b 2 of preselector VW, lead b 4, choke coil Dr 3, earth. Relay C 2 having been energized, the relay V 5 is energized over: earth, contact 89 c 2, winding II of relay C 2, contact 91 a 3, relay V 5, 100 battery, earth. At contact 87 v 5 (make before break) is closed a locking circuit for relay T 1 over the resistance Wi. After its winding I has been disconnected, the relay C 2 locks itself over winding II in the previously described circuit for energizing relay V 5.

By transmitting further trains of impulses the driving magnets of the not shown switches (Fig. 1, GW 4 and LW 4) can be operated to position the latter in the main exchange HVSt1. This takes place as follows:

When relay A 3 is operated and before relay V 5 has been energized, the closing of contact 97 a 3 energizes the relay C 3 in the main exchange HVSt1 (Fig. 4) over: earth, contacts 98 v 5, 97 a 3, 100 v 7, lead b 6, contact 105 v 10, off-normal contact 106 h 3 of group selector GW 4, contact 108 v 8, relay C 3, battery, earth. The closing of contact 120 c 3 energizes the relay V 8 over: earth, contact 120 c 3, relay V 8, battery, earth. By closing its contact 117 v 8, the relay V 8 locks itself over: earth, contacts 117 v 8, 118 s 1, 119 a 4, relay V 8, battery, earth. When shortly after relay A 3 has been operated the relay V 5 is energized in the sub-exchange UVSt1 the contact 98 v 5 opens the circuit for energizing the relay C 3, which falls back and opens its contact 120 c 3. The impulses

transmitted by the subscriber cause the relay A 3 to fall back in known manner at each impulse; hence in the main exchange HVSt 1 the relay A 4 is energized at each impulse over: earth, contacts 104 c 2, 102 a 3, lead a 6 of the junction line VL, relay A 4, battery, earth. The first time relay A 4 energizes, its contact 119 a 4 opens the short circuit, so that the relay V 9 is energized over: earth, contacts 117 v 8, 118 s 1, relay V 9, relay V 8, battery, earth. Similarly, the removal of a short circuit (contact 91 a 3) in the sub-exchange UVSt 1 causes relay V 6 to be energized over: earth, contacts 89 c 2, 90 a 3, relay V 6, relay V 5, battery, earth. Both relays remain energized for the duration of the impulse train, and only fall back after the impulses have ceased owing to the short circuit over the contact 119 a 4 and 91 a 3. While these relays are energized, the relays V 7 (earth, contact 92 v 6, relay V 7, battery, earth) and V 10 (earth, contact 114 v 9, relay V 10, battery, earth) are energized. The group selector GW 4 can then be positioned onto the wanted junction line by means of impulses received by the relay A 4 in the main exchange.

For example, if the transmitted impulse train does not consist of 3, 4, 7 or 8 impulses, 30 the group selector GW 4 in known manner will test the junction line reached over arm c 7 owing to relay P 1 being connected up over: earth, contact 113 v 8, windings I and II of relay P 1. If the line be free, the relay 35 P 1 is energized in known manner and the junction line VL is switched through to the junction line seized by the group selector GW 4.

The modification using level contacts on the 40 selector switch GW4 will first be described. In this case the lead b6 of the junction line VL is connected to the level contacts k78 and k34, that is, the points 1 and 2 are permanently connected.

If the first impulse train received at the 45 main exchange HVSt1 consists of three or four impulses, the level contact k 34 of the group selector GW 4 is mechanically operated when the third or fourth level is reached. 50 Thereby the following circuit is established: earth, battery, resistance Wi, level contact k 34 of the group selector GW 4, contact connection 1, 2, lead b 6 of the junction line VL, contact 101 v 7, windings I of the relays 55 H 1 and H 2, earth. Owing to the insertion of the resistance Wi in this circuit, only the relay H 1 is operated, and at the end of the impulse train this circuit is again disconnected at the contact 101 v 7, because, as previously 60 mentioned, at the end of the impulse train the relay V 6 is released and by opening its contact 92 v 6 it also causes the release of the relay V 7. Before the windings I of the relays H 1 and H 2 have been disconnected, 65 the relay H 1 closes a locking circuit for itself

over: earth, contacts 94 c 2, 93 h 1, winding II of relay H 1, battery, earth. By closing the contact 82 h 1 the relay Q (Fig. 2) is energized over: earth, battery, winding I of relay Q, contacts 33 h 34 a, wiper e 2 of the preselector VW, lead e 4, contacts 82 h 1, 83 h 2, earth. Relay Q locks itself over its contact 8 q in the circuit: earth, contacts 7 a, 8 q, winding II of relay Q, battery, earth. Contact 37 q opens the test circuit extending over wiper d 2 of the preselector, while the closing of contact 38 q prepares a test circuit over wiper e 2 of the preselector. Furthermore, the opening of contact 37 q releases relay T 1; hence the rotary magnet D 2 of preselector VW is energized over: earth, battery, rotary magnet D 2 of preselector VW, contact 60 s 59 a, 58 t 1, 57 h, relay interrupter RU 2, earth, after relays H and Y have been released by the opening of contact 21 t 1. In addition, the opening of contact 42 q releases relay U and then the opening of contact 46 u releases relay X. The preselector VW is moved on; hence, first the relay A 3 (Fig. 4) falls back and at contact 90 a 3 it short circuits the relay C 2 which opens its contacts 89 c 2 and 94 c 2. Thereby the relays V 5 and H 1 are also released.

At the time the level contact k 34 of the group selector GW 4 closes the circuit of the relay H 1, it also closes a circuit for relay S 1 over: earth, battery, resistance Wi, level contact k 34, contact connection 1—2, contact 105 v 10, off-normal contact 107 k 3, winding I of relay S 1, earth. Relay S 1 closes a locking circuit for its winding II over: earth, contacts 115 s 1, 116 v 8, winding II of relay S 1, battery, earth. At the same time it opens the circuit of relay V 8 at contact 118 s 1 and short circuits relay P 1 at contact 109 s 1, thereby bringing about the release of the group selector GW 4. The locking circuit of relay S 1 is opened at contact 116 v 8 by the release of relay V 8.

With its wiper e 2 the preselector VW tests a free junction line going to the sub-exchange UVSt 3 shown in the Fig. 5. When it finds such a line (Fig. 5, a5, b5, e5), a circuit is closed over: earth, battery, windings I and II of relay T 1, contacts 41 a, 39 s, 38 q, wiper e 2 of preselector VW, lead e 5, winding I of relay C 1, off-normal contact 76 k 1, rotary off-normal contact 77 w 1, earth. Relays T 1 and C 1 are energized in this circuit. The opening of contact 58 t 1 arrests the preselector VW and the closing of contact 21 t 1 energizes the relays H and Y. At contacts 23 t 1 and 29 t 1 the junction line is switched through to the leads a 5 and b 5; hence the relay A 2 is energized over the subscriber's loop. The closing of contact 79 c 1 establishes a circuit for locking relay C 1 and for energizing relay V 3 over: earth, contact 79 c 1, winding II of relay C 1, contact 81 a 2, relay V 3, battery, earth. The closing of con-

tact 78 *v* 3 connects a shunt circuit to the lead *e* 5 over the resistance *Wi*. By transmitting further impulse trains (2, 2, 1) the subscriber *Tn* 1 can then reach the wanted 5 subscriber (e. g. *Tn* 4) of the sub-exchange.

If the impulse train transmitted after pre-selector *VW* has been set on the connecting device of the main exchange *HVSt* 1 comprises 7 or 8 impulses instead of 3 or 4 impulses, the level contact *k* 78 is mechanically operated by the group selector *GW* 4 at the 10 end of the impulse train. The following circuit is established: earth, battery, level contact *k* 78, contact connection 1, 2, lead *b* 6 of the junction line *VL*, contact 101 *v* 7, windings *I* of relays *H* 1 and *H* 2, earth. Relays *H* 1 and *H* 2 are operated in this circuit and lock themselves over: earth, contacts 94 *c* 2, 93 *h* 1, winding *II* of relay *H* 1, battery, earth, and over: earth, contacts 94 *c* 2, 95 *h* 2, winding *II* of relay *H* 2, battery, earth. At the 20 same time at contact *k* 78 the relay *S* 1 is energized over: earth, battery, level contact *k* 78, contact connection 1, 2, contact 105 *v* 10, off-normal contact 107 *k* 3 of group selector *GW* 4, winding *I* of relay *S* 1, earth. The 25 energizing of relay *S* 1 is followed by the release of the connecting devices in the main exchange *HVSt* 1 in the manner already described.

The energizing of the relays *H* 1 and *H* 2 causes the test circuit extending over the wiper *d* 2 of pre-selector *VW* to be opened and thus is interrupted the circuit of the relays *T* 1 and *U*. The closing of contact 35 *u* prepares a test circuit over wiper *c* 2 of pre-selector *VW*. After relay *T* 1 has fallen back, the rotary magnet *D* 2 of pre-selector *VW* is energized over: earth, battery, rotary magnet *D* 2, contacts 60 *s*, 59 *a*, 58 *t* 1, 57 *h*, relay interrupter *RU* 2, earth, after relays *H* and *Y* have been released by the opening of contact 21 *t* 1. Pre-selector *VW* is moved on and relay *A* 3 (Fig. 4) falls back. The 40 short circuiting of winding *II* of relay *C* 2 at contact 90 *a* 3 causes this relay to fall back and at contact 89 *c* 2 to open the circuit of relay *V* 5. In addition, the locking circuits of relays *H* 1 and *H* 2 are opened at 45 contact 94 *c* 2.

Over its wiper *c* 2 the pre-selector *VW* now tests for a free connecting device in the same sub-exchange *UVSt* 1. This connecting device (*GW* 1) may be the same as that previously referred to for setting up a connection to a subscriber of the same sub-exchange; namely, leads *a* 3, *b* 3, *c* 3, *d* 3, *e* 3 and the group selector *GW* 1.

The setting up of the connection now takes place in the manner already described. The subscriber *Tn* 1, by dialling (digit 2), sets the connecting device (Fig. 1, *GW* 1) onto a contact, to which is connected a junction line going to the sub-exchange *UVSt* 2. By 60 transmitting further impulse trains (digits 65

2, 2, 1) and thus positioning the connecting devices (*GW* 2 and *LW* 2 in Fig. 1) in the sub-exchange *UVSt* 2, the subscriber can then reach the subscriber *Tn* 5 (Fig. 1) of the sub-exchange *UVSt* 2.

Upon the release of the connection, the call seeker *AS* and pre-selector *VW* are released when the receiver is hung up owing to the relay *A* 1 being released; hence, when relays *C* and *V* 1 are released, relay *T* 1 falls back 70 and effects the release of the relays *H*, *Y*, and *A*. The opening of contact 27 *a* releases the relays *P* and *T*, and the opening of contact 7 *a* releases the relay *V*. Thus, the call seeker *AS* and pre-selector *VW* are rendered 75 free for another call.

Instead of effecting the switching over into the various traffic directions by actuating different level contacts (*k* 34, *k* 78), it is possible to do it by means of an auxiliary switch 80 *MW* as shown in Fig. 4. In that case, the contact connection between the points 1 and 2 is replaced by a connection between the points 1 and 2'. This arrangement then operates in the following manner: When the relay *A* 4 falls back at each impulse during the transmission of the impulse train, as already described, the auxiliary switch *MW* is positioned at the same time as the group selector *GW* 4 owing to the rotary magnet being energized in the circuit: earth, battery, rotary magnet *D* 3 of the auxiliary switch *MW*, contacts 121 *v* 9, 122 *a* 4, rotary off-normal contact 123 *w* 3, contact 125 *v* 8, earth, in accordance with the transmitted impulses.

If the transmitted impulse train comprises 85 3 or 4 impulses, the wiper *d* 31 of the auxiliary switch is positioned onto the third or fourth contact. Hence, when relay *V* 9 is released at the end of the impulse train, a 90 circuit for energizing the relay *H* 1 is established over: earth, battery, contacts 127 *v* 8, 126 *v* 9, wiper *d* 31 of the auxiliary switch *MW*, resistance *Wi*, contact terminals 2', 1, lead *b* 6 of junction line *VL*, contact 101 *v* 7, winding *I* of relay *H* 1 and of relay *H* 2, earth. As 95 previously mentioned, the resistance *Wi* prevents the relay *H* 2 being operated. Therefore, the closing of the contact 82 *h* 1 effects 100 the switching over of the pre-selector *VW* to the sub-exchange *UVSt* 3, as already described.

If the impulse train comprises 7 or 8 impulses, the wiper *d* 31 of the auxiliary switch 105 *MW* stands on the contact 7 or 8 at the end of the impulse train; hence, over the lead *b* 6 a circuit is now established in which the relays *H* 1 and *H* 2 are operated. The opening of the contacts 84 *h* 1 and 85 *h* 2 then causes the 110 previously described return to a connecting device in the sub-exchange *UVSt* 1.

Instead of using a two-wire junction line *VL* (*a* 6, *b* 6), it is possible to use three-wire junction lines (*a* 6, *b* 6, *c* 6) in accordance 115

with Figs. 6 and 7. The circuit changes taking place are the same as those described above. In the Fig. 6 the relay C 3 is energized in the same manner as in Fig. 4, except that

5 its circuit extends over a third lead *c* 6 instead of over the lead *b* 6 of the junction line *VL*.

In the Fig. 7 the third lead *c* 6 of the junction line *VL* is used for controlling the relays *H* 1 and *H* 2 in accordance with the transmitted impulse train.

We have seen that every subscriber who wants to speak to a subscriber of another exchange has to dial a particular number (0). Thereby in accordance with the example a 15 simplification of the telephone directory is effected as regards numbering, and in addition the unnecessary seizing of the heavily loaded outgoing lines to the main exchange is avoided when the subscriber wants a subscriber of the same exchange.

What is claimed is:

1. In a telephone system, an automatic switch, three groups of trunks accessible to said switch, means for operating said switch 25 to select a trunk in one group, and means responsive to a digit transmitted over the selected trunk for reoperating said switch to select a trunk in the second or third group depending on the value of the digit.

30 2. In a telephone system, an automatic switch, means for operating said switch to select a second switch, means controlled from the second switch for causing the first switch to select a third switch, and means controlled 35 from said third switch for causing said first switch to select a fourth switch.

3. In a telephone system, two sub-exchanges and a main exchange, a non-numerical hunting switch in the first sub-exchange, 40 a numerical switch accessible to said hunting switch, local trunks and trunks to the second sub-exchange accessible to said numerical switch, and trunks to the main exchange accessible to said non-numerical hunting switch.

45 4. In a telephone system, three sub-exchanges and a main exchange, a non-numerical hunting switch in the first sub-exchange, a numerical switch accessible to said hunting switch, local trunks and trunks to the second sub-exchange accessible to said numerical switch, and two groups of trunks extending to the third sub-exchange and to the main exchange, respectively, accessible to said hunting switch.

55 5. In a telephone system, a main exchange and a number of sub-exchanges, a non-numerical hunting switch in the first sub-exchange, means responsive to the seizure of said switch for operating same to select one 60 of a group of local trunks, means responsive to a digit dialled and dependent upon the value of the digit for reoperating said switch to select one of a group of trunks to the main exchange, and means responsive to the succeeding digit dialled, providing said digit

indicates a different traffic direction, for releasing said main office trunk and reoperating said switch to select the proper traffic direction.

6. In a telephone system, a sub-exchange including a non-numerical hunting switch, a trunk extending to a main exchange, two relays in the trunk at the sub-exchange controlled over one conductor of said trunk, means for operating said hunting switch to select said trunk, means in the main exchange responsive to a digit dialled for returning a signaling current to operate the first of said relays to indicate a particular traffic direction, and means in the main exchange responsive to a different digit dialled for returning a different signaling current to operate both of said relays to indicate another traffic direction.

7. In a telephone system, a plurality of sub-exchanges and a main exchange, a non-numerical hunting switch in the first of said sub-exchanges, a numerical switch accessible to said hunting switch, means controlled from said numerical switch responsive to a digit dialled and depending on the value of said digit for causing said hunting switch to select one of a group of trunks to the main exchange, two relays in said trunk at the sub-exchange, means in the main exchange responsive to the

90 succeeding digit dialled and depending on the value of said digit for returning a signaling current over said trunk to operate the first of said relays to indicate a particular traffic direction, and means responsive to a different digit dialled and depending on the value of said digit for returning a different signaling current over said trunk line to operate both of said relays to indicate a different traffic direction.

95 8. In a telephone system, an exchange including two automatic switches, a trunk line extending to a second exchange and terminating in an automatic switch, means responsive to the seizure of the first of said switches for seizing the second of said switches, means responsive to the operation of said second switch to a predetermined position for releasing same and for reoperating said first switch to seize said trunk line, means responsive to the operation of said switch in said second exchange over said trunk line to a predetermined position for releasing same and for reoperating said first switch in said first exchange to again seize said second switch.

100 9. In a telephone system, an exchange including a non-numerical switch, a station having a dial, means responsive to the removal of the receiver at said station for seizing said switch and for operating same to a first position, means responsive to the operation of said dial and dependent upon the digit dialled for causing said switch to operate to a second position, and means responsive to the succeeding operation of the dial and depend-

ent upon the next digit dialled for causing said switch to again operate to said first position.

10. In a telephone system, an exchange including two automatic switches and a station equipped with a dial, a trunk line extending to a second exchange, a second trunk line extending to a third exchange, means responsive to the removal of the receiver at said station for causing said first switch to seize said second switch, means responsive to the 5 operation of said second switch by said dial and dependent upon the digit dialled for releasing same and causing said first switch to reoperate to seize said first trunk line, and means in said second exchange responsive to the succeeding operation of said dial and dependent upon the digit dialled for causing said first switch to reoperate to either seize 15 said second trunk line or again seize said second switch.

11. In a telephone system, a non-numerical hunting switch having access to three groups of trunks, means responsive to the seizure of 20 said switch for operating same to select an idle trunk in the first of said groups, means responsive to a predetermined digit transmitted over the selected trunk for reoperating said switch to select an idle trunk in the 25 second of said groups, and means responsive to a predetermined digit transmitted over said second selected trunk for reoperating said switch to select an idle trunk in the third of said groups.

30 12. In a telephone system, a non-numerical hunting switch having access to three groups of trunks, means responsive to the seizure of said switch for operating same to select an idle trunk in the first of said groups, means responsive to a predetermined digit transmitted over the selected trunk for reoperating said switch to select an idle trunk in the second of said groups, and means responsive to a digit transmitted over said second selected trunk and dependent on the value thereof for reoperating said switch to either select an idle trunk in the third of said groups or again select an idle trunk in said first group.

35 13. In a telephone system, an exchange having local trunks and trunks extending to a second exchange, a subscriber's station equipped with a dial in said first exchange, means responsive to the removal of the receiver at said station for extending a connection to one of said local trunks, and means responsive to the dialling of a particular digit for releasing said local trunk and extending a connection to one of the trunks to said second exchange.

40 14. In a telephone system, an exchange having local trunks and trunks extending to a second and a third exchange, a subscriber's station equipped with a dial in said first exchange, means responsive to the removal of the receiver at said station for extending a connection to one of said local trunks, and means responsive to the dialling of a particular digit for releasing said local trunk and extending a connection to one of the trunks to said second exchange.

45 the receiver at said station for extending a connection to one of said local trunks, means responsive to the dialling of a particular digit for releasing said local trunk and extending a connection to one of the trunks to said second exchange, and means responsive to the dialling of a succeeding digit of predetermined value for releasing the trunk to the second exchange and extending a connection to one of the trunks to said third exchange.

50 15. In a telephone system, an exchange having local trunks and trunks extending to a second exchange, a subscriber's station in said first exchange equipped with a dial, means responsive to the removal of the receiver at said station for extending a connection to one of said local trunks, means responsive to the dialling of a predetermined digit for releasing said local trunk and extending a connection to one of the trunks to said second exchange, and means responsive to the dialling of another digit of predetermined value for releasing the trunk to the second exchange and again extending a connection 55 to one of said local trunks.

55 16. In a telephone system, three exchanges, a non-numerical hunting switch and a numerical switch in the first exchange, trunks to the second exchange accessible to said numerical switch, trunks to the third exchange accessible to said hunting switch, and means responsive to the seizure of said hunting switch for operating same to seize said numerical switch.

60 In witness whereof, I hereunto subscribe my name this 19th day of April, A. D. 1929.
GERHARD RADKE.
